UNITED STATES PATENT OFFICE.

BERNARD P. FALTIN, OF BAREVILLE, PENNSYLVANIA.

QUICK-RETURN PUMP-HEAD GEARING.

1,398,684.

Specification of Letters Patent. Patented Nov. 29, 1921.

Application filed November 12, 1919. Serial No. 337,511.

To all whom it may concern:

Be it known that I, BERNARD P. FALTIN, a citizen of the United States, residing at Bareville, in the county of Lancaster and State of Pennsylvania, have invented certain new and useful Improvements in Quick-Return Pump-Head Gearing; and I do hereby declare the following to be a full, clear, and exact description of the invention, such as will enable others skilled in the art to which it appertains to make and use the same.

The invention for which I seek a patent relates to a reversing change gearing, particularly intended to be applied to the pump-head-gearing of dispensing pumps in which rotation of the operating handle in one direction, as on the discharging or working stroke, imparts a relatively slow movement to the pump piston, and rotation of the operating handle in the opposite direction, as on the idle stroke, imparts a relatively rapid return movement to the piston.

I have designed my mechanism with particular reference to pumps used at gasolene supply and sales stations, but it will be apparent that it is not limited to such use but is of very broad application.

My invention consists in general, of a reversible driving member, a driven member, differential speed-transmission devices between the driving and driven members, means for automatically clutching the lower speed differential transmission to the driving member that is rendered effective by a movement of the driving member in one direction, means for automatically clutching the higher speed differential transmission to the driving member, rendered effective by a movement of the driving member in the reverse direction, and a means responsive to the clutch-engaging movement of the clutch for the higher speed transmission, that positively holds the other clutch in disengaging or retracted position; and it particularly consists in the combination of a driving shaft having thereon gears of different sizes adapted to be selectively interlocked with the driving shaft in order to be selectively driven thereby, with a counter shaft having gears of different sizes rigidly mounted thereon, the selective interlocking devices being oppositely engaging, spring biased, one-way clutch members or pawls, and means whereby the one-way clutch member or pawl for the high speed driving gear, when engaged will hold the clutch member

for the low speed driving gear out of engaging position, in order, under such conditions, to avoid locking of the gears due to the rotation of the low speed pinion faster than the drive shaft and in a direction to interlock with its clutch on the drive shaft.

My invention also comprises certain details more fully set forth in the descriptive portion of this specification and illustrated in the accompanying drawings.

Figure 1 is a plan view of a pump head gearing embodying my invention.

Fig. 2 is a section on the line *a—a* of Fig. 1.

Fig. 3 is a perspective, partly in section, of the high and low speed selective driving gears, separated, and the bearing member for them on the driving shaft.

Fig. 4 is a section through the bearing member on the driving shaft.

Fig. 5 is an end elevation of the member shown in Fig. 4, but with a part broken away.

Fig. 6 is an elevation of the part shown in Fig. 4, viewed from a different angle.

Referring to the drawings forming a part of this application:

A designates the side plates of a frame work or housing for supporting a gear mechanism embodying my invention, *B* and *C* are stay-bolts securing the side plates of the frame work or housing together. Journaled in the said side plates are two rotary shafts 17 and 21, the shaft 17 having one end projecting outside the frame work and carrying a hand crank 18, or the like, secured to it.

The shaft 17 is the prime power shaft or driver, and carries a small and a large gear 15 and 12, respectively, one or the other of which is adapted to be turned by the shaft 17 dependent on the direction of rotation of said shaft. Fixed to the shaft 21, which is a driven or counter shaft, are two driven gear wheels 20 and 19, of different sizes, the larger driven gear 20 intermeshing with the smaller driving gear 15, and the smaller driven gear 19 intermeshing with the larger driving gear 12. A pump piston operating rack 22 is in mesh with the smaller driven gear 19. The construction is such, as will be more specifically pointed out hereinafter, that rotation of the crank 18 and shaft 17 in a clockwise or right hand direction will automatically effect the interlocking of the small gear wheel 15 with the shaft 17, and

this will rotate the gear 20 and through it the shaft 21 and gear 19 in counter-clockwise or left hand direction, thereby elevating the rack 22 slowly and powerfully; and 5 rotation of the crank 18 and shaft 17 in a counter clockwise direction will automatically effect the interlocking of the large gear wheel 12 and the drive shaft 17, and this will rotate the gear 19 directly in a 10 clockwise direction thereby lowering the rack 22 quickly.

I will now describe what I deem to be an important part of my invention, to wit, the mechanism whereby, in response to the rotation of the driving shaft in one direction (the liquid discharging stroke of the piston) the low speed gear 15 will be automatically interlocked with said shaft, and in response to its rotation in the opposite direction (the idle or return stroke of the piston) the high speed gear 12 will be interlocked 20 with said shaft.

Integral with, or securely fastened to the shaft 17, so as to turn therewith, is a cylindrical hub or bearing member 11. This bearing member 11 has a slot 10 formed in it extending in a direction to one side of the center or on planes forming a chord of the circumference of the said bearing member. 25 As shown in the drawing, and as a convenience in machining, merely, I may form the bearing member 11 with two central hubs and secure the flat rings 13 and 14 thereover in order to close the ends of the 30 slot 10, and form guiding surfaces for two pawls 2 and 3 which operate in the said slot. The ring 14 is of sufficient width to form a flange extending circumferentially beyond the general cylindrical surface of the 35 bearing member. At the bottom of the slot 10 are two bore-holes 10'. Each of the pawls 2 and 3 has a reduced shank adapted to enter respectively in one of the bore holes. The shank of the pawl 2 is surrounded by a 40 spiral compression spring 8, while the shank of the pawl 3 is surrounded by a similar compression spring 9, which is, however of greater strength than the spring 8. These 45 springs are seated in the bore holes, and bear upon shoulders formed on the pawls at 50 the shank junction and tend to press the pawls outward, the spring 9 pressing with greater force than the spring 8, as stated. A rock arm 4 is pivoted within the slot 10 55 on the pin 5. The two pawls 2 and 3 have cavities milled on their opposing edges, and the ends of the rocker arm 4 are seated in said cavities. The cavity 3' in the pawl 3 is of such size and form that the end of the 60 rocker arm that coöperates therewith fits without lost motion, and no movement of either pawl 3 or rocker arm 4 can take place without a corresponding movement of the other. The cavity 2' in pawl 2, however, is 65 of such size and form as to provide a lost

motion connection between pawl 2 and the rocker arm. Normally, as shown in Figs. 3, 4 and 5, the superior strength of spring 9 as compared with spring 8 will tend to maintain the pawl 3 in its projected position 70 and the pawl 2 in its retracted position, the end of the rocker arm 5 that engages the pawl 2 being then against the inner end of the lost-motion cavity in the side of the pawl 2. Should now any pressure be applied to the pawl 3 whereby it is pressed inward, the end of rocker arm 5 that engages pawl 2 will be moved outward, and the spring 8 will cause the pawl 2 to follow, whereby the pawl 2 will be projected by 80 spring pressure until stopped by the cessation of movement of the rocker arm, against the end of which the spring 8 will have forced the inner shoulder of the lost-motion cavity 2' in said pawl 2. In this position, 85 with the pawl 3 forced inward the pawl 2 may be freely pushed inward against spring tension to the limit permitted by the length of the cavity therein and when released said pawl 2 will spring outward again wholly 90 independent of the pawl 3, and without imparting any motion to said pawl 3. Under the last named conditions, in other words, pawl 2 acts as an ordinary spring pressed pawl. 95

The outer end of pawl 3 is beveled in the same manner as an ordinary latch-bolt, whereas I prefer to form the end of pawl 2 square, as shown in the drawings, the end lying in a plane at right angles to its sides 100 and edges. The proportions and limits of movement of said pawl 2 are such that, when retracted, as it is when the pawl 3 is projected, the end face of said pawl 2 is wholly within the perimeter of the bearing member 11; 105 but when projected the rearward corner is flush with the perimeter or does not project beyond it, while the front or ratchet-engaging corner stands well out from the perimeter. The guiding slot 10, lying, as it does, 110 in planes parallel with but spaced from a diametrical plane, permits of this construction. The described form of pawl 2 is important as this form is that of greatest strength, and the pawl 2 bears the strain of 115 the load on the pumping strokes.

The large driving gear 12 is of annular form and fits nicely over the bearing member 11 against the flange on ring 14. In its inner circumference is a notch forming an 120 internal ratchet shoulder 7 adapted to engage the pawl 3 when in registry therewith. Except when prevented by the engagement of said pawl and ratchet shoulder, the gear 12 is adapted to rotate relatively to the 125 member 11.

The small driving gear 15 is formed to fit over the shaft 17 and has, preferably integral with it, an axially extended, hollow, cylindrical member or hub portion 16 fit- 130

ting over the bearing member 11, and having a notch and ratchet shoulder 6, eight angular in section, and a counter part of the engaging end of pawl 2 with which it co-operates. The gear 15, with its hub 16, is adapted to rotate freely on the member 11, except when prevented by the engagement of pawl 2 with ratchet shoulder 6.

Assuming now the rack 22 to be in its 10 lowermost position and the operator to have hold of the crank handle, it will be apparent that by rotating the crank handle and connected prime mover shaft clockwise, or in a right hand direction, (viewed as in 15 Figs. 1 and 2, or from the side nearest the gears 12, 19 and rack 22) the pawl 2 will be carried around within the hub 16 of the low speed gear 15 until it registers with the notch and ratchet shoulder 6, after which 20 gear 15 will rotate positively with the power shaft 17, and as gear 15 meshes with larger gear 20 secured or formed on counter shaft 21, that shaft with the affixed gears will rotate counter-clockwise or left handedly. 25 The gear 19, meshing with the rack 22 will elevate the latter with a relatively slow movement and thus effect, in the use for which I have designed this apparatus, a slow and powerful liquid delivering stroke. 30 Meantime the gear 12 will click over the pawl 3, rotating at this time more slowly on the bearing 11 and in the same direction.

Having completed the slow upward working stroke of the rack 22, the operator then 35 reverses the motion of the crank in order to lower the rack to the position for starting the next working stroke, this downward stroke being the idle one, which it is desirable to effect quickly. In the reverse or counter-clockwise rotation of the shaft 17, the pawl 2 will be immediately pressed back and slip around within the hub 16 of gear 15. As soon as pawl 3, comes into registration 40 with the notch and ratchet shoulder 7 within high speed gear 12, the said pawl will snap into engagement therewith under the influence of the strong spring 9, and thereafter carry the gear 12 around with 45 the shaft 17 as long as reverse rotation of said shaft continues. As soon as the pawl 50 3 is projected outward by its spring 9 the rocker arm 4 will engage the inner shoulder of the lateral cavity of pawl 2 and by 55 reason of the preponderance of strength of spring 9 over that of spring 8, will hold pawl 2 retracted so that it will not engage the ratchet shoulder 6 as the gear 15 turns rapidly relatively to the bearing 11 and 60 overruns said pawl 2. Large gear wheel 12 being now rotated positively and in mesh with small rack-engaging gear 19, which is now turning in a clockwise direction, will 65 obviously run the rack 22 downward at a speed accelerated over that of its prior up-

ward movement, although the speed with which the operator turns the crank has not been changed. Assuming that the high speed gears 12 and 19 have a ratio of 2 to 1, and the low speed gears 15 and 20 have 70 a ratio of 1 to 2, it will be obvious that with the same speed of handle in both directions the rack 22 will be returned on its idle stroke at a speed four times that with which it is elevated on its working stroke. 75 The load of the rack and its connected parts and the normal friction of the moving parts will obviously afford sufficient resistance to prevent the gears 12 and 15 from moving with the shaft 17 and bearing member 11 80 except when one or the other of the pawls is properly engaged.

The provisions for automatically holding the pawl 2 retracted when the pawl 3 is engaged with the high speed gear 12 but allowing pawl 2 to act freely as a spring pawl when the pawl 3 is retracted, whereby locking off the gears is prevented during the high speed return movement; and the square ended pawl for interlocking with the low speed driving gear when it acts as a driver, in its particular relation to the co-operating parts, are deemed valuable features of my invention.

Were it not for the rocker arm 4 and the lost-motion cavity in the edge of pawl 2 with which one end of the rocker arm engages, it is apparent that the gearing would lock during the reverse or high speed return movement, because at that time the low speed gear 15 is rotating on the bearing 11 at a considerably higher speed than said bearing and in the same direction, which is such as to cause the driving side of the pawl 2 to interlock with the shoulder 6 as soon 100 as the two register. By disposing the slot 10 in the bearing member 11 in the relative position shown I am enabled to give the pawl 2, which carries the heavier load, great strength by the construction shown. The 105 other pawl 3 carrying a lighter load need not be of such strength; therefore I bevel its end and seat it in the same slot 10 as that in which the pawl 2 is seated, and this forms a structure economical to manufacture. 110

By properly designing the speed ratios of the change speed gearing, any desirable difference of speed on its upward and downward movements may be imparted, without 115 possibility of locking the gearing on its quick return movement. It is possible to so design these ratios that the pawls cannot both register with the ratchet shoulders of the gears at the same moment.

Having thus described my invention what I claim as new and desire to secure by Letters Patent is the following:

1. The combination of a reversible driving member, a driven member, differential 120

transmission means between the driving and the driven member, an automatic clutching device comprising a part that moves responsive to the movement of the driving member in one direction to couple the lower speed element of the transmission to said driving member, another automatic clutching device comprising a part that moves responsive to the reverse movement of the driving member to couple the higher speed element of the transmission to said driving member, the said parts being movable with respect to each other, and a means operating in response to the reverse movement of the reversible driving member for holding the clutching device for the low speed mechanism in an inoperative position.

2. The combination of a reversible driving member, a driven member, differential transmission means between the driving and the driven member, an automatic clutching device responsive to the movement of the driving member in one direction to couple the lower speed element of the transmission to said driving member, another automatic clutching device responsive to the reverse movement of the driving member to couple the higher speed element of the transmission to said driving member, and a means responding to the movement of the high speed clutching device into its clutching position during said reverse movement, for holding the clutching device for the low speed mechanism in an inoperative position.

3. The combination of a reversible driving shaft, a counter shaft having two gears secured thereon, differential gears on the driving shaft, one-way clutch devices respectively arranged to drive in opposite directions, one clutch device adapted to drive a low speed gear and the other a high speed gear of the said differential gears, means to bias both clutch devices into position to engage both said low and high speed gears, and a means, responsive to the engaging movement of the clutch device for the high speed gear, for holding the clutch device for the low speed gear in inoperative position.

4. The combination of a reversible driving shaft, a counter shaft, a variable speed gearing connecting the driving shaft and counter shaft comprising two gears of different sizes secure on the counter shaft and two gears of different sizes revoluble on the driving shaft but adapted to be clutched thereto, and in mesh with the gears on the counter shaft, a one-way clutch device biased toward clutching position for each gear on the driving shaft, one arranged to drive the smaller gear in one direction, and the other arranged to drive the larger gear in the reverse direction, the bias of the clutch for the larger gear being the stronger, and means responding to the engaging movement of the clutch device for the larger gear, for holding the clutch

device for the smaller gear in inoperative position, said means including a lost motion connection effective when the larger gear clutch device is in inoperative position, to permit the other to operate independently. 70

5. In a variable speed reversing gearing, two shafts, differential gearing connecting them, comprising two differently sized gears upon one shaft, one adapted to be rotated in one direction and the other in the opposite 75 direction, two one-way acting, spring-pressed clutch mechanisms for effecting such rotations, and means whereby the clutch mechanism for the small gear may be held in inoperative position while the other is in operative position. 80

6. A reversely rotatable shaft, a pair of bodies rotatable thereon, two oppositely facing spring pressed pawls seated on the shaft, the spring of one being stronger than that 85 of the other, a ratchet shoulder on each body adapted to engage one of said pawls, a device for transmitting the engaging movement of the pawl with the stronger spring to the pawl having the weaker spring, and a 90 lost motion connection between said transmitting device and said pawl with the weaker spring, whereby when said pawl with the stronger spring is retracted the other pawl is free to ratchet. 95

7. A reversely rotatable shaft, a pair of bodies rotatable thereon, two oppositely facing spring pressed pawls seated on said shaft, the spring of one being stronger than that of the other, a ratchet shoulder on each 100 body adapted to engage a pawl, a rocker member extending between the pawls, and having a lost motion connection with one of them.

8. A reversely rotatable shaft having 105 guiding seats extending in planes cutting the shaft at one side of its center, oppositely facing automatic clutching devices guided in said seats, a pair of bodies rotatable on the shaft but each of which is adapted to be clutched thereto by one or the other of the clutching devices according to the direction of rotation of the shaft, one of said clutching devices having a right angled end and the other having a beveled end. 110

9. In a differential reverse gearing, a rotatable shaft, an enlarged bearing member thereon, a gear ring journaled on the bearing, a smaller gear sleeved on the shaft and having an enlarged hub sleeved upon the enlarged bearing member. 120

10. In a differential reverse gearing a rotatable shaft, an enlarged bearing member thereon having a pawl-carrying slot, pawls seated in the slot, a gear ring sleeved in the bearing member and adapted to be engaged by one pawl, a gear sleeved upon the shaft and having a lateral hub sleeved upon the bearing member, and adapted to be engaged by the other pawl. 125

11. The combination of a reversible driving member, a driven member, differential transmission means between them, oppositely facing, one way automatic clutches including two relatively movable members adapted to connect the driving member with a high or low speed member of the differential transmission means, and means whereby to interrupt the automatic action of the 10 clutch for the low speed transmission during operative engagement of the clutch for the high speed transmission.

12. A quick return mechanism comprising a driving member, a reversible driven mem-

ber, two variable speed members operatively 15 connected to the driven member, two spring pressed clutch elements on the driving member arranged to engage said variable speed members, respectively, to drive them in opposite directions, and means whereby the 20 clutch element that engages the low speed member of the variable speed members is held out of engagement in response to the movement of the other clutch element into engaging position.

25

In testimony whereof I affix my signature.

BERNARD P. FALTIN.
